Primary Examiner — W. A. Teddy Falloway*(74) Attorney, Agent, or Firm* — John M. Lipchitz(57) **CLAIM**

The ornamental design for a package for a shaving razor cartridge as shown and described.

DESCRIPTION

FIG. 1 is a front perspective view of a package for a shaving razor cartridge showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front bottom perspective view thereof; and,

FIG. 9 is a rear perspective view thereof.

The dot-dash broken lines represent the bounds of the claim and form no part of the claimed design. The dash-dash broken lines illustrate environment and form no part of the claimed design.
